UNITED STATES PATENT OFFICE.

WILLIAM P. JONES, OF ARCADE, NEW YORK.

IMPROVEMENT IN HAY-RACKS.

Specification forming part of Letters Patent No. 122,387, dated January 2, 1872.

SPECIFICATION.

I, WILLIAM P. JONES, of Arcade, in the county of Wyoming and State of New York, have invented certain Improvements in "Hay-Racks," of which the following is a specification:

The object of my invention is to provide a rack which may be easily removed from the wagon or cart, and which will occupy but little space when not in use; and it consists in hinging together the inner extremities of the cross-bars of hay-racks, which are provided with swinging and detachable standards.

In the drawing, Figure 1 is a plan view of my improved hay-rack. Fig. 2 is a vertical section at the dotted line *x*, Fig. 1. Fig. 3 is an end elevation.

A is the rack-body, constructed with side pieces and bottom *G*, in the usual manner. *B* *B* are the extensions or wings of the rack, composed of horizontal slats *a*, and girts *b*, suitably bolted together, and the latter resting upon and extending within the side pieces of the body in the ordinary manner. The body *A* is made in two sections, being divided longitudinally through the center, as indicated in Figs. 1 and 3, and the girts *b* meet at this division line and are secured to the bottom *C*. Thus it will be seen that the sections of the rack may be lifted separately over the bolster-stakes of the wagon and removed, as indicated by heavy dotted lines in Fig. 3. For the purpose of locking the sections together I provide hinges, *c*, Figs. 1 and 3, constructed in any convenient form, and preferably secured to the adjacent ends of the girts. Bolts with nuts or pins are used for the pintles of these hinges, and are removable, whereby the sections may be separated by removing the pintles, or folded up, as indicated in light dotted lines in Fig. 3, and removed together. By this means, when laid away it occupies only about one-half the

space usually required by racks of this description. In order to avoid the trouble of removing the bolts or pintles from the hinges *c*, the latter may consist of a hook and loop attached, respectively, to the opposite sections of the rack, as indicated in Fig. 4, whereby, when a section is raised over the bolster-stake, as shown in heavy dotted lines in Fig. 3, the hook draws out of the loop, allowing the sections to separate. By this plan of constructing the rack in two parts it may be readily placed upon or removed from the wagon by one person. The standard *D* is made in the usual form, with bent uprights and connecting-girts, and the lower ends of the former are fitted to enter sockets *o*, Figs. 2, 3, and 5, the main shank of which revolves easily in the side pieces of the body *A*. Spring-stops *n*, Figs. 1 and 2, are secured to the box, projecting outward against the uprights and retaining them in a vertical position. These springs may be pressed out of the way when necessary, and the standard allowed to pass them and swing down when not in use. Thus it will be seen that when the rack is taken apart or folded up this standard may be removed from the sockets *o*; but when in use it is retained in its vertical position, or may be folded down upon the bottom *C*, as shown by dotted lines in Fig. 2, when the wagon is unloaded.

What I claim as my invention is—

A hay-rack provided with a swinging and detachable standard *D*, as and for the purposes set forth, and composed of two longitudinal sections, the cross-arms or girts *b* of which are hinged together at their inner extremities, as shown and described, for the purposes specified.

WILLIAM P. JONES.
